(57) **CLAIM**

The ornamental design for a wipes dispensing canister base mounting bracket, as shown and described.

DESCRIPTION

FIG. 1 is a perspective view of a wipes dispensing canister base mounting bracket of the new design;

FIG. 2 is a top plan view of the wipes dispensing canister base mounting bracket of the new design

FIG. 3 is a front elevational view of the wipes dispensing canister base mounting bracket of FIG. 1;

FIG. 4 is a bottom view of the wipes dispensing canister base mounting bracket of FIG. 1;

FIG. 5 is a rear elevational view of the wipes dispensing canister base mounting bracket of FIG. 1;

FIG. 6 is a right side elevational view of the wipes dispensing canister base mounting bracket of FIG. 1;

FIG. 7 is a left side elevational view of the wipes dispensing canister base mounting bracket of FIG. 1; and,

FIG. 8 is a perspective view of the wipes dispensing canister base mounting bracket of FIG. 1 with a wipes dispensing canister.

The broken lines shown in the Figures represent environment and portions of the wipes dispensing canister wall mounting bracket that form no part of the claimed design.

1 Claim, 5 Drawing Sheets
